CHAIR-DESK STRUCTURE

Sumner C. Willis, White Plains, and Danforth Cardozo, Jr., New York, N. Y., assignors to American Seating Company, Grand Rapids, Mich., a corporation of New Jersey

Application December 15, 1951, Serial No. 261,856

13 Claims. (Cl. 155—128)

1

The present invention relates to classroom furniture and more particularly to combination chair-desk units.

The primary objects of the invention are to provide an improved chair-desk for use in classrooms or other appropriate places; to provide such a unit in which an arm or shelf is mounted on the upper end of a post at one corner of the chair, the shelf being useful to the chair occupant as a support for books while reading and as a support for paper and the occupant's arm while writing, and for like purposes; to provide such a unit in which the shelf is forwardly-rearwardly adjustable and also angularly adjustable with reference to the chair; to provide such a unit in which the forward-rearward and angular adjustments of the shelf may be made quickly, easily, quietly, and simultaneously; to provide such an adjustable shelf which may if desired be applied to some support other than a chair post; and in general to provide a chair-desk unit which is especially convenient in use and attractive in appearance.

An illustrative embodiment of the invention is shown in the accompanying drawings, wherein:

Figure 1 is a perspective view of a chair-desk unit embodying the invention;

Figure 2 is a fragmentary side elevational view of the shelf-supporting chair post and shelf mounted thereon, the shelf being shown in a horizontal position in full lines and being indicated in inclined positions in dotted lines and broken lines;

Figure 3 is a side elevational view of the shelf shown in one horizontal position in full lines and indicated in a different forwardly-rearwardly adjusted horizontal position in dotted lines;

Figure 4 is a rear elevational view of the shelf shown in one horizontal position in full lines and indicated in a slightly laterally moved position in dotted lines;

Figure 5 is a fragmentary perspective view of the underside of the shelf and the supporting structure therefor;

Figure 6 is an enlarged fragmentary top plan view of the shelf and the supporting structure therefor, a portion of the shelf being broken away to reveal the structure below the shelf;

Figure 7 is a side elevational view of the same shown partly in vertical section taken on line 7—7 of Figure 8;

Figure 8 is a rear elevational view of the same, showing in one laterally moved position in full lines and in another laterally moved position in dotted lines; and

2

Figure 9 is a greatly enlarged fragmentary horizontal sectional view of parts thereof taken on line 9—9 of Figures 7 and 8.

Referring now in detail to these drawings, wherein like parts are designated by the same numerals in the several views, the chair there shown is, per se, of generally conventional form, comprising side frames 10, a seat 11, and back rails 12. On one of the front corners of the chair 10—the right front corner as here shown—is mounted an upright support or column 13 preferably fabricated of metal tubing and secured as by welding to the front leg portion of the right hand side frame 10, and this post 13 serves as a support for the tablet arm or shelf 14 and the mounting structure therefor.

An upstanding post 15 is telescopically fitted within the column 13 and is secured therein in vertically adjusted position by means of a clamp 20. To the upper end of the post 15 is fixedly secured, as by welding, a transverse sleeve fitting 17, and a tubular metal shaft 18 is secured in the sleeve fitting 17 as by means of a set screw 19. The shaft 17 is thus fixedly secured to the upper end of the post 15 and extends laterally therefrom on both sides of the post.

A supporting bracket 20 is here shown fabricated from a metal sheet cut and shaped to form a pair of spaced bearing portions 21, 22 which are turnably and laterally shiftably mounted on the shaft 18 on opposite sides of the post 15, and a body portion 23 extending forwardly from the bearing portions 21, 22. The body portion 23 of the bracket is provided with forwardly-rearwardly extending runner guides 24 at the opposite sides thereof which, as best shown in Figure 8, extend from said body portion upwardly, then outwardly, then downwardly and finally inwardly. Medially of these guides 24 and forwardly of the post 15, the body portion of the bracket 20 is flanged downwardly to form a cross-sectionally U-shaped depending hanger 25, and one of the side flanges of the hanger, here designated 26 constitutes a latch element and is provided with a plurality of keeper notches 27 therethrough arranged in an arc concentric with the axis of the shaft 18. A cooperating latch element is secured to the upper end of the post 15, and comprises a cross-sectionally inverted U-shaped member 28 (see Figures 6, 7, and 9) secured as by welding to the upper end of the post 15, extending forwardly from the post and into the hanger 25 of the bracket 20. The side flanges or plates of the member 28 are triangular and the side plate 55 designated 29, which lies adjacent the side flange

26 of the hanger 25, has a laterally extending latch 30 thereon adapted to fit into one or another of the keeper notches 27 in said side flange 26.

As best seen in Figure 9, the left hand end of the tubular shaft 18 has inwardly turned lugs 31 thereon, and the right hand end of the bracket's bearing portion 22 is closed by an end wall 32. A helical compression spring 33 is disposed within the tubular shaft 18 and bears at one end against the lugs 31 on the shaft and at its other end against the end wall 32 of the bracket's bearing portion 22. This compression spring 33 serves to normally urge the bracket 20 to the left as viewed in Figures 4, 5, 8 and 9, toward its position in which the latch 30 engages in one or another of the keeper notches 27 thus to secure the bracket in a selected turned position.

The writing shelf 14 has on its underside a plate 34 secured thereto as by screws 35, the opposite side marginal edges of which are bent to form runners 36 which forwardly-rearwardly slidably embrace the guides 24 on bracket 20, and the shelf 14 is thus mounted on the bracket slidably to selected forwardly-rearwardly adjusted positions. The shelf 14 is thus also laterally shiftable with the bracket 20 and turnable with said bracket to a substantially horizontal position and to selected positions of rearward-downward inclination with reference to the chair. Stop means are associated with the post 15 and the shelf 14 for securing the shelf in forwardly-rearwardly adjusted positions. To this end, the plate 34 has in its medial portion, but slightly to the left of the post 15, a forwardly-rearwardly extending rack comprising downwardly formed teeth 37 having cut out notches 38 therebetween. A detent 39 on the upper end of the post's fixed sleeve fitting 17 is adapted to engage in one or another of said notches 38 when the bracket 20 and shelf 14 are shifted to the right by the force of spring 33, thus to secure the shelf in selected forwardly-rearwardly slid positions of adjustment.

Operation

When the occupant of the chair-desk desires to adjust the shelf 14, he may adjust it both forwardly-rearwardly and angularly at the same time. In order to do this, he merely grasps the shelf 14 and shifts it slightly to the left as indicated in dotted lines in Figure 4. This slight shifting movement of the shelf also shifts the bracket 20 to the left, thus simultaneously disengaging the latch means, i. e. latch 30 in one of the keeper notches 27, and the stop means, i. e. detent 39 in one of the rack notches 38. Disengagement of the cooperating latch means permits turning of the shelf and bracket about shaft 18 to the selected angle of tilt, and disengagement of the cooperating stop means permits simultaneous forward-rearward adjustment of the shelf 14 on the bracket 20 to the selected position. When the chair occupant releases the shelf 14, spring 33 returns the shelf and bracket to their normal position wherein the latch means and the stop means are both engaged to secure the shelf in adjusted position.

It will readily be seen that the shelf 14 may be similarly adjustably mounted on any suitable upright support by means of the mounting structure herein described, and that the invention is therefore not limited to use with a chair-desk; and while but one specific embodiment of the invention has been shown in the drawings, numerous details may be altered or omitted without

departing from the spirit of the invention as the same is defined by the following claims.

We claim:

1. In a chair-desk structure: a chair provided with an upstanding post at one of the front corners thereof; a bracket laterally shiftably mounted on the upper end of the post; a shelf forwardly-rearwardly slidably mounted on the bracket; and cooperating stop means associated with the post and the shelf whereby the shelf may be secured in selected forwardly-rearwardly adjusted positions on the bracket, the stop means on the shelf being engaged with and disengaged from the stop means on the post by opposite lateral shifting movements of the shelf and bracket.

2. In a chair-desk structure: a chair provided with an upstanding post at one of the front corners thereof; a bracket laterally shiftably mounted on the upper end of the post; a shelf forwardly-rearwardly slidably mounted on the bracket; and cooperating stop means associated with the post and the shelf whereby the shelf may be secured in selected forwardly-rearwardly adjusted positions on the bracket, the stop means on the shelf being engaged with and disengaged from the stop means on the post by opposite lateral shifting movements of the shelf and bracket; and spring means associated with the post and the bracket for normally urging said shelf and bracket to their laterally shifted position wherein said cooperating stop means are engaged.

3. In a chair-desk structure: a chair provided with an upstanding post at one of the front corners thereof; a substantially horizontal shaft fixedly secured to the upper end of the post and extending laterally therefrom; a bracket laterally shiftably mounted on said shaft and provided with forwardly-rearwardly extending guides at the opposite sides thereof; a shelf having on its underside a pair of runners slidably disposed in the bracket's guides whereby the shelf may be moved forwardly and rearwardly to selected positions of adjustment, said shelf having also on its underside a rack extending forwardly-rearwardly between the runners; an upstanding detent on the post engageable with the rack whereby the shelf may be secured in selected forwardly-rearwardly adjusted positions, said detent being engaged in and disengaged from one or another of the rack's notches by opposite lateral shifting movements of the shelf and bracket.

4. In a chair-desk structure: a chair provided with an upstanding post at one of the front corners thereof; a substantially horizontal tubular shaft fixedly secured to the upper end of the post and extending laterally therefrom; a bracket laterally shiftably mounted on said shaft and provided with forwardly-rearwardly extending guides at the opposite sides thereof; a shelf having on its underside a pair of runners slidably disposed in the bracket's guides whereby the shelf may be moved forwardly and rearwardly to selected positions of adjustment, said shelf having also on its underside a rack extending forwardly-rearwardly between the runners; an upstanding detent on the post engageable with the rack whereby the shelf may be secured in selected forwardly-rearwardly adjusted positions, said detent being engaged in and disengaged from one or another of the rack's notches by opposite lateral shifting movements of the shelf and bracket; and a compression spring

disposed within the tubular shaft and bearing at one end against means fixed on the shaft and at its other end against means fixed on the bracket for normally urging said shelf and bracket toward their laterally shifted position wherein said detent engages in one of said rack's notches.

5. In a chair-desk structure: a chair provided with an upstanding post at one of the front corners thereof; a bracket mounted on the upper end of the post turnably about a substantially horizontal axis extending laterally of the chair; a shelf forwardly-rearwardly slidably mounted on the bracket, said shelf being turnable with the bracket to a substantially horizontal position and to positions of rearward-downward inclination with reference to the chair; cooperating stop means associated with the post and the shelf whereby the shelf may be secured in selected forwardly-rearwardly adjusted positions on the bracket; and cooperating latch means associated with the post and the bracket whereby the bracket and shelf may be secured in selected turned positions.

6. In a chair-desk structure: a chair provided with an upstanding post at one of the front corners thereof; a bracket mounted on the upper end of the post laterally shiftably and turnably about a substantially horizontal axis extending laterally of the chair; a shelf forwardly-rearwardly slidably mounted on the bracket, said shelf being turnable with the bracket to a substantially horizontal position and to positions of rearward-downward inclination with reference to the chair; cooperating stop means associated with the post and the shelf whereby the shelf may be secured in selected forwardly-rearwardly adjusted positions on the bracket; and cooperating latch means associated with the post and the bracket whereby the bracket and shelf may be secured in selected turned positions; said cooperating stop means and said cooperating latch means being simultaneously engaged and simultaneously disengaged by opposite lateral shifting movements of the shelf and bracket.

7. In a chair-desk structure: a chair provided with an upstanding post at one of the front corners thereof; a bracket mounted on the upper end of the post laterally shiftably and turnably about a substantially horizontal axis extending laterally of the chair; a shelf forwardly-rearwardly slidably mounted on the bracket, said shelf being turnable with the bracket to a substantially horizontal position and to positions of rearward-downward inclination with reference to the chair; cooperating stop means associated with the post and the shelf whereby the shelf may be secured in selected forwardly-rearwardly adjusted positions on the bracket; and cooperating latch means associated with the post and the bracket whereby the bracket and shelf may be secured in selected turned positions; said cooperating stop means and said cooperating latch means being simultaneously engaged and simultaneously disengaged by opposite lateral shifting movements of the shelf and bracket; and spring means associated with the post and the bracket for normally urging said shelf and bracket to their laterally shifted position wherein said cooperating stop means and said cooperating latch means are engaged.

8. In a chair-desk structure: a chair provided with an upstanding post at one of the front corners thereof; a substantially horizontal shaft fixedly secured to the upper end of the post and

extending laterally therefrom; a bracket having a bearing portion turnably and laterally shiftably mounted on the shaft, said bracket having a body portion extending forwardly from said bearing portion; a shelf forwardly-rearwardly slidably mounted on the body portion of the bracket, said shelf being also turnable with the bracket to a substantially horizontal position and to positions of rearward-downward inclination with reference to the chair; cooperating stop means associated with the post and the shelf whereby the shelf may be secured in selected forwardly-rearwardly adjusted positions on the bracket; cooperating latch means associated with the post and the bracket whereby the bracket and shelf may be secured in selected turned positions; said cooperating stop means and said cooperating latch means being simultaneously engaged and simultaneously disengaged by opposite lateral shifting movements of the shelf and bracket on said shaft.

9. In a chair-desk structure: a chair provided with an upstanding post at one of the front corners thereof; a substantially horizontal tubular shaft fixedly secured to the upper end of the post and extending laterally therefrom; a bracket having a bearing portion turnably and laterally shiftably mounted on the shaft, said bracket having a body portion extending forwardly from said bearing portion; a shelf forwardly-rearwardly slidably mounted on the body portion of the bracket, said shelf being also turnable with the bracket to a substantially horizontal position and to positions of rearward-downward inclination with reference to the chair; cooperating stop means associated with the post and the shelf whereby the shelf may be secured in selected forwardly-rearwardly adjusted positions on the bracket; cooperating latch means associated with the post and the bracket whereby the bracket and shelf may be secured in selected turned positions; said cooperating stop means and said cooperating latch means being simultaneously engaged and simultaneously disengaged by opposite lateral shifting movements of the shelf and bracket on said shaft; and a compression spring disposed within the tubular shaft and bearing at one end against means fixed on the shaft and at its other end against means fixed on the bracket for normally urging said shelf and bracket toward their laterally shifted position wherein said cooperating stop means and said cooperating latch means are engaged.

10. In a chair-desk structure: a chair provided with an upstanding post at one of the front corners thereof; a substantially horizontal tubular shaft fixedly secured to the upper end of the post and extending laterally therefrom on both sides of the post; a bracket having a pair of bearing portions turnably and laterally shiftably mounted on the shaft on opposite sides of the post, said bracket having a body portion extending forwardly from said bearing portions and provided with forwardly-rearwardly extending guides at the opposite sides thereof, said body portion having also a latch element comprising a flange depending medially between said guides and provided with a plurality of keeper notches therethrough arranged in an arc concentric with the axis of said shaft; a cooperating latch element secured to the upper end of the post and comprising a plate extending forwardly from the post alongside said flange and provided with a latch engageable in one or another of said keeper notches when said bracket is shifted laterally on the shaft to a position of engagement, whereby

to secure the bracket in selected turned position; a shelf mounted on the body portion of the bracket and turnable therewith to a substantially horizontal position and to positions of rearward-downward inclination with reference to the chair, said shelf having on its underside a pair of runners slidably disposed in the bracket's guides whereby the shelf may be moved forwardly and rearwardly to selected positions of adjustment, said shelf having also on its underside a rack 10 extending forwardly-rearwardly between the runners; an upstanding detent on the post engageable with the rack when the bracket and shelf are shifted laterally to a position of engagement, whereby to secure the shelf in selected forwardly-rearwardly adjusted positions on the bracket; and a compression spring disposed within the tubular shaft and bearing at one end against means fixed on the shaft and at its other end against means fixed on the bracket whereby 15 the bracket and shelf are normally urged to the aforesaid positions of engagement, said rack and detent and said latch elements being simultaneously disengaged by lateral shifting of the bracket and shelf against the pressure of said 20 spring.

11. In a structure of the class described: an upright support; a shaft secured to the upper end of said support and extending substantially horizontally therefrom; a bracket having a bearing portion turnably and longitudinally shiftably mounted on said shaft; a shelf mounted on the bracket for sliding movement in a direction transverse the axis of the shaft, said shelf being also longitudinally shiftable with the bracket and turnable with the bracket to a substantially horizontal position and to positions of inclination; cooperating stop means associated with the shelf and the support whereby the shelf may be secured in a selected slid position on the bracket; cooperating latch means associated with the bracket and the support whereby the bracket and shelf may be secured in selected turned position on the shaft; said cooperating stop means and said cooperating latch means being simultaneously engaged and simultaneously disengaged by opposite longitudinal shifting movements of the shelf and bracket on said shaft.

12. In a structure of the class described: an upright support; a shaft secured to the upper end of said support and extending substantially horizontally therefrom; a bracket having a bearing portion turnably and longitudinally shiftably mounted on said shaft; a shelf mounted on the bracket for sliding movement in a direction transverse the axis of the shaft, said shelf being also longitudinally shiftable with the bracket and turnable with the bracket to a substantially horizontal position and to positions of inclination; cooperating stop means associated with the shelf and the support whereby the shelf may be secured in a selected slid position on the bracket;

cooperating latch means associated with the bracket and the support whereby the bracket and shelf may be secured in selected turned position on the shaft; said cooperating stop means and said cooperating latch means being simultaneously engaged and simultaneously disengaged by opposite longitudinal shifting movements of the shelf and bracket on said shaft; and spring means associated with the support and the bracket for normally urging said bracket and shelf toward their longitudinally shifted position wherein said cooperating stop means and said cooperating latch means are engaged.

13. In a structure of the class described: an upright support; a tubular shaft secured to the upper end of said support and extending substantially horizontally therefrom; a bracket having a bearing portion turnably and longitudinally shiftably mounted on said shaft; a shelf mounted on the bracket for sliding movement in a direction transverse the axis of the shaft, said shelf being also longitudinally shiftable with the bracket and turnable with the bracket to a substantially horizontal position and to positions of inclination; cooperating stop means associated with the shelf and the support whereby the shelf may be secured in a selected slid position on the bracket; cooperating latch means associated with the bracket and the support whereby the bracket and shelf may be secured in selected turned position on the shaft; said cooperating stop means and said cooperating latch means being simultaneously engaged and simultaneously disengaged by opposite longitudinal shifting movements of the shelf and bracket on said shaft; and a compression spring disposed within the tubular shaft and bearing at one end against means fixed on the shaft and at its other end against means fixed on the bracket for normally urging said bracket and shelf toward their longitudinally shifted position wherein said cooperating stop means and said cooperating latch means are engaged.
